UNITED STATES PATENT OFFICE.

CHARLES ANDERSON, OF SOUTH BEND, INDIANA, ASSIGNOR TO THE SOUTH BEND IRON WORKS, OF SAME PLACE.

PLOW-POINT.

SPECIFICATION forming part of Letters Patent No. 592,858, dated November 2, 1897.

Application filed March 13, 1897. Serial No. 627,367. (No model.)

To all whom it may concern:

Be it known that I, CHARLES ANDERSON, a resident of South Bend, in the county of St. Joseph and State of Indiana, have invented 5 certain new and useful Improvements in Plow-Points; and I do hereby declare the following to be a full, clear, and exact description of the invention, such as will enable others skilled in the art to which it appertains 10 to make and use the same.

My invention relates to an improvement in plow-points, the object being to economize in the manufacture, thereby decreasing the initial expense of production, and turn out a 15 more durable and efficient article of manufacture.

In the accompanying drawings, Figure 1 is a view of the improved point. Fig. 2 is a section. Fig. 3 is a view of the chill.

20 A represents the plow-point, and B is the chill. The plow-point has a slightly-concaved upper surface, as at 1, (see Fig. 2,) like the concaved blade of a razor, so that as the edge wears back it retains its same cutting qualities until the blade is worn up to the body of the point. On this concaved surface parallel 25 ribs 2 2 are formed. Now it will be seen that the point of a plow wears away the fastest at the cutting edge or blade, where it pushes its 30 way through the unbroken ground. By providing these ribs this comparatively thin self-sharpening edge is strengthened and reinforced and caused to scour perfectly, the soil following the direction of the ribs and grooves, 35 leaving a bright and shining surface. In this way the blade or cutting-edge portion is stronger than if thicker, and it has the superior quality which the thin edge possesses of self-sharpening until it becomes entirely worn 40 away. This wearing is even. It is upon the blade portion and likewise upon the ribs, and the same uniformity of strength is preserved throughout the entire life of the point.

Hitherto longitudinal ribs have been formed 45 on the under surface of the plow-point. These ribs have stopped a little short of the extreme edge—say three-sixteenths back from the edge. This margin only was chilled, and the idea was that the chilled margin 50 should wear away after a few days' use,

whereupon a serrated cutting edge would be formed; but there are two manifest objections present in said invention which my construction obviates. These are, first, that whatever gums up or sticks to the under side of a 55 point always remains there, and when there are ribs and grooves this tendency is only aggravated, because there is absolutely no friction at that point to wear the accumulating material away, and with the ribs and grooves 60 it only sticks the more tenaciously. Again, the margin is the only portion which is chilled and made hard. In my own invention I place my ribs for a different purpose—namely, 65 to give strength, not to form teeth or serrations—and to prevent clogging and adhesion of foreign substances they are located where there is constant friction—to wit, on the top surface—so that I provide a comparatively thin edge, which I make strong by the employment of the ribs at a point where they 70 will not cause gumming and clogging of the plow.

Having fully described my invention, what I claim as new, and desire to secure by Letters Patent, is—

1. A plow-point constructed with a smooth flat lower surface and provided on its upper surface with parallel strengthening-ribs, the cutting edge being made thin and its extreme 80 forward edge made practically straight and without serrations and indentations, and the upper surface of the cutting edge of the point being chilled, substantially as set forth.

2. A plow-point constructed with a smooth 85 flat lower surface and provided with a comparatively wide thin cutting edge having parallel strengthening-ribs on its upper surface, said ribs being gradually diminished in thickness at their opposite ends, the point having 90 its cutting edge chilled through and through, substantially as set forth.

In testimony whereof I have signed this specification in the presence of two subscribing witnesses.

CHARLES ANDERSON.
